UNITED STATES PATENT OFFICE

CHRIS S. VAN HORN, OF BLOOMSBURG, PENNSYLVANIA

CARVING INSTRUMENT

Application filed January 9, 1930. Serial No. 419,674.

This invention relates to improvements in carving instrument, and is more particularly directed toward an instrument for carving wax or similar solid or plastic material.

As is well known in many arts, it is necessary to cut away the surface of a solid or plastic body to bring it to a desired external shape. Thus, in the dental art, after a cavity has been cut to the desired shape, it is filled with wax and a wax pattern thus prepared. It is necessary to carve this model in order to bring it to the desired form. The present invention is particularly adapted for employment in the dental art, in which small and delicate models are being prepared.

According to the present invention, a carving instrument is provided which may be employed either by pushing or pulling for obtaining the desired shaping of the wax model, since by its construction it easily and smoothly follows the tooth form in shaping, cusps, sulci and contours of occlusal, buccal and lingual aspects. Particularly, the particular angle or rake of the posterior or anterior cutting edge frees the instrument from liability of digging into the wax model, so that definite shavings may be removed at each cut, the thickness of the shaving being regulated by the angle of presentment to the work and the pressure, etc., as exerted by the operator. It is thus possible to prepare the most delicate and "feather-edged" margins with a clean and true carving and without danger of fracturing or chipping the wax.

One example of construction of such an instrument is shown by way of example on the accompanying drawing, in which:

Figure 1 is a view of such a carving instrument as a whole.

Fig. 2 is a side elevation of the same on an enlarged scale.

Fig. 3 is a corresponding face elevation on the same scale as Fig. 2.

Figs. 4 and 5 are successive sectional views of the same substantially on lines 4-4 and 5-5 of Fig. 3.

Figs. 6 and 7 are elevational views in the direction of the arrows 6 and 7 in Fig. 2.

In the drawing, the handle 10 of the tool

is provided at one end with any desired shaping instrument 11 for interproximal preparation, for example, while at the other end it is provided with an offset goose-neck 12 which carries at its outer end the cutting head. This cutting head extends in the illustrated example transversely and symmetrically with respect to the line of the stem and goose-neck in Fig. 3, having two pointed ends 13, 14 at its lateral extremities. The terminal surfaces of the tool as a whole, which may be hereinafter referred to as the bottom surfaces since they are at the lower part of the illustrative figures, are substantially symmetrical and are designated at 15, 16 in Figs. 4 and 5, joining one another at a ridge which extends from end 13 to end 14 and lying along an arc and being substantially in a plane.

The upper surfaces are preferably of differing dimensions, the anterior surface 17 being wider than the posterior surface 18: these two surfaces, however, preferably blend into one another by a transverse curve. It will be noted from Fig. 2 that the goose-neck supports the head at a position in the rear of the line of direction 19 of the stem: and that the posterior upper surface 17 lies substantially in a plane forming an angle A with this line of direction 19, of about 35°: while the angle B of the posterior upper surfaces, near the goose-neck, is slightly greater, being of the order of 40°. Also, it will be noted that the central element 20 of the posterior lower surface may be substantially at a right angle with respect to the line of direction 19, while corresponding elements 21 of the posterior lower surface are almost parallel to the line of direction 19.

As will be noted from Fig. 6, the head preferably is symmetrical with respect to the stem, and has the anterior cutting edge 22 and the posterior cutting edges 23, the latter being separated from the goose-neck 12 by slight indentations: as is to be seen from Fig. 7, the posterior surface of the goose-neck blends smoothly into the posterior lower surface of the head. In the successive sections of Figs. 4 and 5, it will be noted that the head in these successive planes has a lozenge-shaped cross-section, the elements of

the surfaces 15 and 16 being substantially equal, while those of the upper surfaces 17 and 18 are dissimilar, the anterior surface 17 being wider.

5. The instrument may be employed by pulling or pushing. The continuous arcuate anterior cutting edge formed by the junction of the anterior surfaces 15 and 17 being designed more especially to operate mesio-distally (from front to back) or disto-mesially (back to front)--(push or pull), and buccolingually (from cheek to tongue) or linguobuccally (tongue to cheek) when removing rather broad shavings of wax and in preparing the corresponding margins and the marginal ridges. The posterior arcuate cutting edges formed by the junction of the posterior surfaces 16 and 18 serve more especially, in conjunction with the points 13 and 14, and the immediate contiguous anterior cutting edge, in forming the pulpo-occlusal aspect of the cusps and tracing out the sulci in both the required mesio-distal and buccolingual directions, and by reason of the angle employed and the offset position of the head with respect to the line of direction 19 of the stem, the instrument is free of liability to dig into the wax.

What I claim as new and desire to secure by Letters Patent is:

30. 1. A carving tool comprising a stem and a head extending transversely at the end of said stem, said head having a continuous anterior cutting edge for employment by pushing said stem and cutting edge adjacent said stem for employment by pulling said stem.

40. 2. A carving tool comprising a stem and a head, said head extending symmetrically and transversely at the end of the stem and having a continuous anterior cutting edge extending from one end of the head to the other for employment by pushing said stem, and a pair of posterior cutting edges extending from the stem to the respective end of the 45 head for employment by pulling said stem.

50. 3. A carving tool comprising a stem and a head, said stem joining the head by a goose-neck so that the head is posteriorly offset from the line of direction of the stem, said 55 head extending symmetrically on each side of said stem and having a continuous curved, anterior cutting edge substantially lying in a plane and extending from one end of the head to the other, and a pair of posterior cutting edges extending from the goose-neck to the respective end of the head.

60. 4. A carving tool comprising a stem and a head, said head having anterior and posterior upper and lower surfaces so that it is of approximately lozenge-shape in cross-section, the anterior upper surface being located approximately at an angle of 35° to the line of direction of the stem, and the posterior upper 65 surface being located substantially at an an-

gle of 40° to the line of direction of said stem.

5. A carving tool as in claim 4, in which the elements of the anterior lower surface are located approximately at right angles to the line of direction of the stem. 70

6. A carving tool as in claim 4, in which the elements of the posterior lower surface are located substantially parallel to the line of direction of the stem. 75

7. A carving tool comprising a stem having a goose-neck and a head fixed to said goose-neck, said head having an arcuate anterior cutting edge and a pair of arcuate posterior cutting edges, said head being of approximately lozenge-shape cross-section in successive planes parallel to the line of direction of the stem in which the ends of the major diagonal of the lozenge represent the cutting edges. 80

8. A cutting tool as in claim 7, in which the upper anterior surface is broader than the upper posterior surface.

9. A cutting tool as in claim 7, in which the two lower surfaces are substantially symmetrical and joined at an arcuate ridge located substantially in a plane. 90

10. A carving tool comprising a stem and a head, said head having curved anterior and posterior bottom surfaces which meet in a ridge extending from end to end of the head, said surfaces being substantially symmetrical with respect to said ridge and with respect to a plane at a right angle thereto and including the line of direction of said stem, the anterior bottom surface being at the intersection of said latter plane of symmetry substantially at a right angle to the line of the stem and curving slightly in the direction of the stem toward its ends, anterior and posterior top surfaces defining respectively an anterior cutting edge with said anterior bottom surface and posterior cutting edges with said posterior bottom surface, said anterior top surface being substantially a plane. 100

11. A carving tool as in claim 10, in which the plane of the anterior top surface is located at an angle of approximately 35° to the line of direction of the stem. 105

12. A carving tool as in claim 10, in which the stem comprises an offset goose-neck portion joining it with said head, and the exterior surface of the goose-neck merges into the posterior lower surface of the head, and the posterior cutting edges are cut away adjacent the goose-neck. 115

In testimony whereof, I affix my signature.
CHRIS S. VAN HORN.
